GARMENT REINFORCING MEANS

James F. Baker, Troy, Lester L. Almond, North Troy, Frank Ferguson, Troy, and Louis P. Madsen, North Troy, N. Y., assignors to Cluett, Peabody & Co., Inc., Troy, N. Y., a corporation of New York

Application January 16, 1939, Serial No. 251,100

3 Claims. (Cl. 2—265)

This invention pertains to apparel, and relates more particularly to garment reinforcing means designed to resist accidental pulling off of fastener elements, for instance, buttons, during wear or in laundering.

Makers of buttoned garments such as are subject to frequent launderings (for example, men's shirts) are in constant receipt of complaints to the effect that the buttons pull off before the garments have been worn out. Sometimes buttons do come off by reason of breakage of the attaching thread (although the attaching thread is usually relatively strong as compared with the yarns used in weaving the garment fabric) but it is more common for the attaching threads to cut the constituent warp and weft yarns of the fabric so that the button pulls off with the loops of the attaching thread still intact and embracing portions of the garment fabric which are pulled off with the button.

Various expedients have been devised for strengthening those parts of the garment to which the buttons are secured, but since the garment manufacturer, more particularly the makers of men's shirts, is restricted to the use of devices which do not materially alter the appearance of the garment, as compared with ordinary garments of accepted style, no thoroughly satisfactory method insuring a dependable anchorage of shirt buttons has heretofore been devised.

It is true that it has been proposed to use a small stay button at the inside of a heavy garment, such as a man's overcoat, as an anchorage for the regular button at the outer side, but such mode of anchoring buttons is not applicable to garments such as shirts, which are frequently laundered and in which the regular button itself constitutes the maximum of rigid material permissible at any one point.

It has also been proposed to provide the button-supporting front flap of a shirt with a reinforcing strip of textile fabric extending along the edge of said flap and through which the button-attaching stitches pass, but heretofore such stay strips have not provided adequate anchorage to prevent the stitches from pulling out or have been unduly expensive to make and apply, or have been too conspicuous, or have added so much to the thickness of the garment as to be objectionable from the standpoint of appearance or laundering operations.

An object of the invention is to provide a novel stay or reinforce strip furnishing adequate anchorage for the button-attaching thread, which is simple and cheap to make and apply, which does

not detract from the appearance of the garment, and which does not sensibly increase the thickness of the garment or reduce its flexibility.

Other and further objects and advantages of the invention will be made manifest in the following more detailed description and by reference to the annexed drawing, wherein:

Fig. 1 is a fragmentary, elevational, perspective view of the upper part of the inner front flap of a shirt having an attached collar, and buttons by means of which the inner flap is secured to the outer flap; and

Fig. 2 is a diagrammatic section, to large scale, on the line 2—2 of Fig. 1.

Referring to the drawing, the numeral 1 designates the inner front flap of a shirt. This flap is provided with the finished free edge 2 and has an attached collar 3 comprising the neckband 4. A button 5 is secured to the neckband portion of the collar, and a series of buttons 6 (of which but two are shown) is arranged below the collar button 5 and parallel to the finished edge 2 of the inner flap.

As illustrated in Fig. 2, the front flap 1 preferably is provided near its free edge 2 with a reinforce strip 9 of textile material which may, if desired, be like the material of the front flap 1. The edge of the material of the front flap 1 is preferably folded in, as shown at 7, and the edge of the reinforcing strip 9 is also folded in, as shown at 8, the in-folded portions of the front flap and reinforcing strip being registered with each other and being united by a sewed seam 10 so as to form the hemmed and finished edge 2. The opposite marginal portion of the reinforce strip 9 is first folded at 11 so as to form a ply 12 which lies to the rear of the main part of the strip 9. The material is then again folded at 13 so as to overlie the ply 12 and form a pleat 14. The material is then again folded along the line 15 so as to embrace the fold 11 and to dispose the margin 16 of the strip 9 between the front face of such strip and the rear face of the garment flap 1. Thus at this point there are four plies of the reinforce strip disposed behind the material of the garment flap and spaced inwardly from the free edge 12 of the latter, and these four plies are united to the material of the garment flap by a row of stitches 17. The making of this row

of stitches and the folding of the material of the reinforce strip to form the plies may be done in a single operation, by the use of an appropriate folder attachment, in an ordinary sewing machine.

The row of stitches 17 extends substantially

parallel to the finished edge 2 of the garment flap and constitutes a guide useful in applying the buttons 6. These buttons are secured to the front flap of the garment by groups of stitches 18 and 19 which pass through the material of the front flap and through the four superposed plies of the reinforce strip, it being noted that the center of the button is registered with the row of stitches 17 and that the groups of button-attaching stitches 18 and 19 are disposed at opposite sides respectively of the row of stitches 17. These stitches of strong sewing thread closely bind together the constituent yarns of the several plies of material so that immediately behind each button is an area of great firmness, substantially symmetrical with the button and which provides a very secure anchorage for the button-attaching stitches, making it very difficult for the button-attaching stitches to pull out by cutting or breaking the constituent yarns of the fabric.

This type of reinforce is particularly useful when a series of buttons is to be attached, since the reinforcing strip 9, in accordance with this mode of procedure, not only provides reinforcing means for each of the several buttons of the series, but also cooperates with the material of the garment flap to provide the finished edge 2.

While certain desirable embodiments of the invention have been described by way of example, it is to be understood that the invention is not necessarily limited to these precise embodiments but is to be regarded as broadly inclusive of any and all equivalents thereof such as fall within the terms of the appended claims.

We claim:

1. In combination in a shirt comprising overlapping front flaps of which the inner is provided with buttons for engagement with buttonholes in the outer flap, reinforcing means for the button-supporting flap to prevent the buttons from being pulled out, said reinforcing means comprising at least four plies of textile fabric disposed at the rear side of the inner flap of the shirt and united thereto by a row of stitches extending substantially parallel to the free edge of said flap and underlying the centers of the several buttons, and button-attaching means disposed at each side respectively of said row of stitches and uniting each button to the material of the inner flap and to the several plies of reinforcing fabric.

2. The combination with a garment having a hem along one edge thereof, of a facing strip having a similar hem along one edge thereof, the

hemmed edges of the garment and strip being in registry and a row of stitches uniting the strip to the garment and completing said hems, the opposite marginal portion of the facing strip comprising four superposed plies, the material of the strip being turned rearwardly to form a fold line spaced from but parallel to said line of stitches thereby to provide a ply of the strip disposed adjacent to the rear surface of the strip, the material of the strip then turning rearwardly again to overlie said ply and therewith forming a pleat, and then being turned forwardly to embrace the first fold line and having its free margin interposed between the front face of the strip and the material of the garment, stitches uniting the superposed plies of the reinforce strip to the material of the garment, and a fastening element for the garment disposed at the outer side of the latter and substantially symmetrically across said last-named row of stitches, and attaching means passing through said fastener element, the material of the garment, and the several plies of the reinforce strip, such fastening means being disposed at each side respectively of the last-named row of stitches.

3. In combination with a garment including an edge portion provided with buttons for engagement with buttonholes in a complementary part of the garment, said edge portion including a folded-in margin of the material of the garment proper and a folded-in margin of a reinforce strip, said folded-in margins registering with each other and a row of stitches uniting them, said reinforce strip extending inwardly from said row of stitches to a first longitudinal fold thereby forming a first reinforce ply, said reinforce strip extending outwardly from said first longitudinal fold to a second longitudinal fold thereby forming a second reinforce ply, said reinforce strip extending inwardly from said second longitudinal fold to a third longitudinal fold thereby forming a third reinforce ply, said reinforce strip extending outwardly from said third longitudinal fold thereby forming a fourth reinforce ply, a row of stitches uniting the material of the garment and said four reinforce plies, and fastening means uniting each button to the garment material and to the underlying reinforce plies of the reinforce strip.
